UNITED STATES PATENT OFFICE.

CARL SEMMLER, OF WIESBADEN, GERMANY.

PERTAINING TO THE UTILIZATION OF THE WASTE HEAT OF GAS-ENGINES.

1,231,208.

Specification of Letters Patent. Patented June 26, 1917.

Application filed January 24, 1914. Serial No. 814,053.

To all whom it may concern:

Be it known that CARL SEMMLER, a subject of the King of Prussia, residing at 20 Mainzerstrasse, Wiesbaden, in the German Empire, has invented certain new and useful Improvements in or Pertaining to the Utilization of the Waste Heat of Gas-Engines, of which the following is a specification, reference being had to the accompanying drawings.

This invention relates to a method of and apparatus for the utilization of the waste heat of combustion motors and more especially of gas engines.

It has already been proposed to cool exhaust gases while at the same time utilizing their waste heat, by arranging within the exhaust silencer or inclosed outlet a coil supplied with a cooling fluid, but it has not been found practicable by this means to cool the exhaust gases to an extent sufficient to prevent the ignition of the inflammable gases which in the event of repeated misfiring, find their way into the exhaust silencer or outlet pipe and cause damage by explosion therein after the entry of the exhaust gases due to a subsequent charge.

It has also been proposed to arrange steam generators in the exhaust outlet but this plan has not proved satisfactory in practice, as the operation of the steam generators has very soon become seriously impaired by the formation of heat-insulating deposits.

Now the present invention has for its objects, first to cool the exhaust so effectually and to such a low temperature as to render impossible the subsequent ignition of any inflammable gaseous mixture which may find its way into the exhaust outlet in consequence of non-firing, and secondly so to construct the exhaust outlet as to render its destruction impossible even in the event of an explosion. The certainty that the operation of the apparatus cannot be arrested through the destructive effect of an explosion enables the cooling of the gas engine cylinders to be combined with the cooling of the exhaust, a safe and uniform method of cooling being thus obtained while the certainty of continuous operation is still further increased by the fact that, as the cooling medium circulates without loss in a closed circuit, it may consist of distilled water, so

ing deposits on the cooling or heating surfaces.

The accompanying drawings illustrate by way of example one form of apparatus for carrying out the invention; in which Figure 1 is a diagrammatic representation of the apparatus and Fig. 2 is a detail view of a portion thereof.

Referring now to the drawings: The cylinders *a* of the gas engine, are surrounded by cooling jackets *b*. The exhaust gases from the engine cylinders are conveyed by means of an exhaust pipe *c*, which should be as short as possible, to a tubular boiler *d*. Around the exhaust pipe *c* there is arranged a jacketing pipe *c'* connected with the jackets *b* and the water space of the boiler *d* by junction pipes *c₂*, *d₁*. The cooling medium circulates in the space between the tubes *c* and *c₁*, and preferably, as shown in Fig. 2, there is arranged in this space one or more helically wound rods *e* by means of which, while the tubes are structurally reinforced, the water circuit is at the same time prolonged, and the water compelled to travel at uniform speed in a prescribed course, instead of being stopped at corners and thus giving rise to development of steam and consequently to surface-heating.

The exhaust gases, as already stated, pass from the exhaust pipe *c* to the tubular boiler *d* by means of which the taking up of waste heat is mainly effected. To enable this to be done, the exhaust outlet *c* is expanded at *k* to the same diameter as the boiler *d*. The considerable increase of cross sectional area to which this gives rise results in a corresponding decrease of the rate of flow of the exhaust gases, and consequently in a more effectual exchange of heat between the hot gases and the cooling water. In order to insure that the diminution of the speed of the gases due to the widening of the path through which they flow shall not result in the production of uncooled spaces, the arrangement adopted is that known as a tubular boiler, that is to say, the gases flow through the tubes and thence to the exhaust outlet *f* while the cooling medium circulates around the tubes.

It is particularly important not only for the utilization of the waste heat and for preventing the risk of the bursting of the cylinders, but also for effecting the intensive cooling of the gases in the exhaust pipe *c* and

the tubular boiler *d* that the cooling medium should be prevented from developing steam. For this purpose, there is inserted in the circuit of the cooling medium, a pump or like liquid propelling device *g* and a throttling device *h* whereby so high a pressure is maintained in the circuit as to prevent the formation of steam.

The heat taken up by the cooling medium 10 is or may be utilized in a heat exchanging device such as a coil *l*.

What I claim is:—

1. In an apparatus for the utilization of waste heat, a gas engine, an exhaust pipe, a 15 jacket surrounding said exhaust pipe and adapted to contain a heat-absorbing medium, means for feeding said medium in a cycle and through said exhaust pipe-jacket, and a throttling device in said cycle adapted to 20 check the expansion into steam of said medium in front of the throttling device, and permit such expansion back of said device.
2. In an apparatus for the utilization of waste heat, a gas engine, an exhaust pipe, 25 a jacket surrounding said exhaust pipe and adapted to contain a heat-absorbing medium, means for feeding said medium in a cycle and through said exhaust pipe-jacket, a throttling device, a propelling device and an 30 intervening heat exchanging device in said cycle, and means located within said jacket for forcing said medium to follow a predetermined course while flowing through the jacket.
- 35 3. In an apparatus for the utilization of waste heat, a gas engine, an exhaust pipe, a jacket surrounding said exhaust pipe and adapted to contain a heat-absorbing medium, means for feeding said medium

through said exhaust pipe-jacket, a throttling device adapted to check the flow of said medium, and a helically wound rod located within said jacket for forcing said medium to follow a spiral course while flowing through the jacket. 40

4. In an apparatus for the utilization of waste heat, a gas engine provided with a jacket that surrounds the engine cylinder, an exhaust pipe, a jacket surrounding said exhaust pipe, both of said jackets being 50 adapted to contain a heat-absorbing medium, means for consecutively feeding said medium through said jackets and a throttling device adapted to check the flow of said medium. 55

5. In apparatus for the utilization of waste heat, a gas engine, the combination with cylinder jacketing means, of exhaust pipe jacketing means comprising a pipe surrounding the exhaust pipe and a helically wound rod interposed between said exhaust and jacketing pipes, and of a closed pipe circuit connecting said jacketing means with a heat-utilizing device, a pumping device adapted to circulate through said circuit a 60 liquid suitable for absorbing heat, and a pressure regulating device adapted to maintain in said circuit, a pressure sufficiently high to prevent said liquid from becoming 65 vaporized therein. 70

In testimony whereof I have hereunto affixed my signature in presence of two witnesses.

CARL SEMMLER.
